**PORTABLE TRANSMITTER FOR REMOTE
CONTROL OF ELECTRICALLY OPERATED
EQUIPMENT**

James Lindsay, Jr., Maple Heights, Ohio, Robert L. Lind,
San Jose, Calif., and David E. Scott, Royal Oak, Mich.,
assignors to Square D Company, Park Ridge, Ill.

Filed July 12, 1973, Ser. No. 378,757

Term of patent 14 years

Int. Cl. D13—03

U.S. Cl. D26—13 R

FIG. 2

FIG. 3

FIG. 4

FIG. 5

FIG. 6

FIG. 7

FIG. 1 is a perspective view of a portable transmitter for remote control of electrically operated equipment showing our new design;

FIG. 2 is a top plan view thereof;

FIG. 3 is a front elevational view thereof;

FIG. 4 is a left side elevation view thereof;

FIG. 5 is a right side elevational view thereof;

FIG. 6 is a rear elevational view thereof; and

FIG. 7 is a bottom plan view thereof.

We claim:

The ornamental design for a portable transmitter for remote control of electrically operated equipment, substantially as shown.
